US0D1106186S

(12) **United States Design Patent** (10) **Patent No.:** **US D1,106,186 S**
(45) **Date of Patent:** **** Dec. 16, 2025**

(54) **SMARTWATCH**

(71) Applicant: **Hao Tian Chui Innovation Technology (shenzhen) Co., Ltd,**
Shenzhen (CN)

(72) Inventor: **Kaiwen Xiang**, Shenzhen (CN)

(73) Assignee: **Hao Tian Chui Innovation Technology (shenzhen) Co., Ltd,**
Shenzhen (CN)

(**) Term: **15 Years**

(21) Appl. No.: **29/974,689**

(22) Filed: **Nov. 25, 2024**

(51) **LOC (15) Cl.** **14-02**

(52) **U.S. Cl.**

USPC **D14/344**

CLAIM

The ornamental design for a smartwatch, as shown and described.

DESCRIPTION

FIG. 1 is a front perspective view of a smartwatch, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures and lower opacity areas within the broken lines, show portions of the smartwatch that form no part of the claimed design.

1 Claim, 8 Drawing Sheets
